(57) **CLAIM**

The ornamental design for a stackable golf tee shroud, as shown and described.

DESCRIPTION

FIG. 1 is a top perspective view of a first embodiment for a stackable golf tee shroud embodying my design; FIG. 2 is a top plan view of the shroud as shown in FIG. 1; FIG. 3 is a side elevational view of the shroud as shown in FIG. 1, it being understood that all sides are identical; FIG. 4 is a bottom plan view of the shroud as shown in FIG. 1;

FIG. 5 is a perspective view of a second embodiment of a stackable golf tee shroud embodying my design; FIG. 6 is a top plan view of the shroud as shown in FIG. 5; FIG. 7 is a side elevational view of the shroud as shown in FIG. 5, it being understood that all sides are identical; and, FIG. 8 is a bottom plan view of the shroud as shown in FIG. 5.
